UNITED STATES PATENT OFFICE

154,014

DESIGN FOR A WRIST WATCH BRACELET

Eric G. O. Anderson, Cranston, R. I., assignor to
Everfine Jewelry Manufacturing Company,
Providence, R. I., a corporation of Rhode Island

Application December 20, 1946, Serial No. 135,653

Term of patent 7 years

(Cl. D45—4)

To all whom it may concern:

Be it known that I, Eric G. O. Anderson, a citizen of the United States of America, residing at Cranston, in the county of Providence and State of Rhode Island, have invented a new, original, and ornamental Design for a Wrist Watch Bracelet, of which the following is a specification, reference being had to the accompanying drawing, forming part thereof.

Figure 1 is a top plan view of a wrist watch bracelet showing my new design;

Figure 2 is a side elevational view thereof.

The essential feature of my design for a wrist watch bracelet resides in the links comprising the bracelet, which links are characterized by the square center platform flanked on two opposite sides by downwardly sloping, rhomboid-shaped elements, which side elements extend in different directions from the center platform.

I claim:

The ornamental design for a wrist watch bracelet, as shown and described.

ERIC G. O. ANDERSON.
